UNITED STATES PATENT OFFICE

ANTON YURKOVITCH, OF PITTSBURGH, PENNSYLVANIA

ADJUSTABLE FLUE CONNECTION

Application filed December 29, 1931. Serial No. 583,629.

This invention relates to adjustable flue connections and more particularly to a means for fastening a stove pipe in a firm but adjustable position relative to a chimney.

Prior to my invention the connection between a stove pipe and the chimney therefor has been both complicated and unsatisfactory. One especially noted disadvantage was that the arrangement was not such as would accommodate stove pipes of different diameters nor would it accommodate stove pipes entering the chimney at different angles resulting from limitations of space and size. Still other prior structures were not so disposed that they would remain permanently in the initial position but would move or turn eventually until the connection was loosened and hence would leak. Other disadvantages are known to those working in this art and need no further discussion here.

One of the objects of the present invention is the provision of an adjustable flue connection which overcomes the above noted and other defects and disadvantages and which at the same time offers additional advantages peculiar to its own construction.

Another object is to provide a flue pipe connection which will accommodate stove pipes of a considerable range of sizes and will accommodate them at almost any angle from the horizontal.

A further object is to embed a member in the room side of the chimney which will be immovably fixed in position and which can accommodate stove pipes of different sizes entering from different angles from the horizontal.

More specifically my invention has for an object the setting of a ring shaped member in the room side of the chimney so constructed and arranged that the member cannot move and at the same time can receive stove pipes of different diameters entering from different directions and maintain the latter permanently in position.

Other and further objects and advantages will either be pointed out hereinafter or will be apparent to those skilled in this art.

In the accompanying drawing wherein I have illustrated a preferred embodiment of the present invention:

Figure 1 is a perspective view of my invention prior to positioning in the chimney brickwork.

Fig. 2 illustrates a fragmentary portion of

the brick-work of the chimney showing my invention in place therein.

Fig. 3 is a fragmentary portion looking from the center of the device toward the wall thereof at the point where the connection is made.

Fig. 4 is a sectional view of the fastening means and spacer showing the same in position with respect to fragmentary sections of the stove pipe and ring; and

Fig. 5 is a section through a modified form of spacer.

Referring now to the drawing in detail, 10 represents a fragment of the brickwork of a chimney or the like looking at the room side thereof. Embedded in this brickwork is the ring-shaped member or annulus 11 which is made of a suitable metal and which, if preferred, is provided at the front edge thereof with a relatively narrow upstanding flange 12 extending at right angles approximately to the body of the annulus. This annulus or ring-shaped member 11 may either be seamless or may be made as shown from a blank which is bent around into ring shape and the edges or seam 13 welded in any desired way. This ring-shaped member 11 is provided with diametrically opposite key-hole slots 14 having their enlarged portion toward the front edge of the device. On the outside of the ring-shaped member 11 are the two box-like shields 15, these shields being also diametrically opposite and overlying the key-hole slots 14 aforesaid. These shields 15 may be shallow box-like members bent up from suitable blanks. They have side flanges 16 by means of which the shields are secured to the ring-shaped member 11. The connection may be by means of rivets 17 or may be by brazing, welding, or the like or in any other available manner. These box-like shields 15 not only provide diametrically opposite projections on the outside of the ring-shaped member 11 but at the same time they protect the key-hole slots 14 from being clogged with mortar, chips of brick or the like thus preventing their functioning in the manner to be described.

A terminal section of stove pipe 18, for example, may be connected to the ring-shaped member 11 so that the stove pipe section 18 is centrally disposed relative to the ring-shaped member 11 and so that the section 18 may be given any desired angular position from the horizontal, thus adapting the same for con-

nection with any stove pipe regardless of the angle from the horizontal which it assumes due to size or space limitations in the room or relative to the members themselves. 5 This stove pipe section 18 is provided at its rearward edge with the diametrically opposite slots 19 which are clearly shown in the drawing. The stove pipe section may be any conventional or desired material either seamless or provided with an overlapping seam 10 20. With respect both to the stove pipe section 18 and the ring-shaped member 11, the existence or absence of a seam is immaterial so that either seamless tubing or blanks bent 15 and fixed into tube shape may be utilized.

The means for maintaining the stove pipe section 18 in place is shown particularly in Fig. 4. The means comprises a bolt 21 having threads 22 throughout its length and an enlarged, slotted head 23 in the usual manner, but the bolt 21 is square, not round, as clearly appears from Fig. 3 and as is also understandable from Fig. 4 wherein the threads 22 of the bolt are also shown as being only on the corners and not on the sides of the bolt. Such a bolt may be made initially in this manner or it may be made by filing down an ordinary round threaded bolt into square shape. Such an operation would generally 25 remove the threads from the flattened sides of the bolt leaving the threads only on the corners. For use with this bolt is the wing nut 24 which is of course, internally threaded. A washer or other similar member 25 is also utilized for the usual purposes. A spacer member 26 is also provided which in the example shown positions the members as they appear in the drawing. This spacer is, however, variable as to size, that is, a spacer is chosen of such a length as to meet certain requirements which will be now set forth. Such a modified form of spacer is shown at 27 in Fig. 5. The spacers are preferably of metal.

45 In general it has been found that stove pipes vary from a rather small diameter to about seven inches as a maximum. I, therefore, make the diameter of my ring-shaped member 11 more than seven inches and in general the diameter need be only a little more and in a typical example my ring-shaped member has a diameter of $7\frac{1}{8}$ ". This permits the ring-shaped member to accommodate stove pipes up to the maximum size generally used but, of course, in special instances, where larger pipes are to be accommodated the ring-shaped member can be made even larger. Depending upon what size of stove pipe is to be connected a spacer is chosen which represents the difference, that is, a spacer is selected which will maintain the stove pipe and the ring-shaped member at the necessary distance apart.

In utilizing the invention the ring-shaped member 11 is embedded in the brickwork 10

of a chimney substantially flush with the room side thereof and the flange 12 lays flat against the brickwork sealing the joint. Mortar may, for example, be placed under the flange, but in any event, the ring-shaped member cannot rotate or move in the brickwork because the box-like shields 15 are firmly fixed in the mortar and bricks to prevent even the slightest movement. The heads of the bolts are passed into the enlarged forward portion of the key-hole slots and then slid toward the rear, the square shanks of the bolts preventing the bolts themselves from turning in the slots after they are in the slots as is clearly indicated in Fig. 3. The spacers 26 or 27 or spacers of proper size can then be placed on the bolts, and the proper size of spacer is selected for the particular case, whereupon the stove pipe section 18 is passed into the ring-shaped member so that the shanks of the bolts pass into the slots 19 in the rear edge of the stove pipe section 18 and the stove pipe section is pushed inwardly until the bolt shanks abut the extremities of said slots. The washer members 25 are then placed over the ends of the bolts and the wing nuts 24 finally put in place and tightened. It will be seen that the stove pipe section 18 can be pivoted about the bolts so that it can be given any necessary or desired angular position from the horizontal thus enabling it to receive the next section of a stove pipe from a stove in any position which said stove may take in a room. The stove pipe leading from the stove (not shown) telescopes with the forward end of the stove pipe section 18 in the usual manner.

It will thus be apparent that I have provided a simple device which is inexpensive and yet which is fully adapted to effect the functions for which it was designed. Furthermore, the construction is such as to connect with stove pipes at any angle from the horizontal within wide limits and moreover stove pipes of considerably different sizes can be accommodated. The device can be made up as a unit shown in Fig. 1 (either with or without stove pipe section 18) and sold in that form at a very moderate price and can then be placed in the brickwork of a chimney without difficulty. My invention is particularly adapted for use in building new houses so that the ring-shaped member 11 can be built directly into the brickwork of the chimney as the latter is constructed.

The above is intended to be illustrative only and is not to be taken in a limitative sense other than as determinable by the subjoined claims. The members 11 and 18 might be other than round, or either or both might be non-round, to meet special conditions or designs.

What I claim as new and desire to secure by Letters Patent is:

1. In an adjustable flue connection as an

- article of manufacture, a ring adapted to be embedded in the brickwork of a chimney, having diametrically opposite key-hole slots therein, means for preventing rotatory movements of said ring in said brickwork and for protecting said key-hole slots, and radial means extending from said key-hole slots for maintaining a section of stove-pipe in predetermined relationship with said ring.
2. In an adjustable flue connection as an article of manufacture, a ring adapted to be embedded in the brickwork of a chimney, having diametrically opposite key-hole slots therein, means for preventing rotatory movements of said ring in said brickwork and for protecting said key-hole slots, and radially extending means for maintaining a section of stove-pipe in predetermined relationship with said ring, said means cooperating with said key-hole slots at one end and cooperable with the section of stove-pipe at the other end.
3. In an adjustable flue connection as an article of manufacture, a ring adapted to be embedded in the brickwork of a chimney, having diametrically opposite key-hole slots therein, means for preventing rotatory movements of said ring in said brickwork and for protecting said key-hole slots, and radially extending means for maintaining a section of stove-pipe in predetermined relationship with said ring, said means cooperating with said key-hole slots at one end and cooperable with the section of stove-pipe at the other end, which is predeterminedly slotted therefor.
4. An adjustable flue connection as an article of manufacture comprising a ring adapted to be embedded in the brickwork of a chimney flush with the room-side of said chimney, having diametrically opposite key-hole slots therein, means for preventing movement of said ring and for protecting said key-hole slots, a stove-pipe section associated with said ring having diametrically opposite slots, and radially extending means cooperating with said pairs of opposed slots for maintaining said stovepipe section in selective angular relation to said ring whereby stove-pipes at different angles may be connected to said stove-pipe section.
5. An adjustable flue connection comprising a ring adapted to be embedded in the brickwork of a chimney flush with the room-side of said chimney, having diametrically opposite key-hole slots therein, means for preventing movement of said ring and for protecting said key-hole slots, a stove-pipe section having diametrically opposite slots, and means for maintaining said stove-pipe section in desired relation to said ring, said means comprising bolts and nuts extending between said key-hole slots and the slots in the stove-pipe section and a spacer thereon between said ring and stove-pipe section.
6. An adjustable flue connection comprising a ring adapted to be embedded in the brickwork of a chimney flush with the room-side of said chimney, having diametrically opposite key-hole slots therein, means for preventing movement of said ring and for protecting said key-hole slots, a stove-pipe section having diametrically opposite slots, and means for maintaining said stove-pipe section in desired relation to said ring, said means comprising bolts and nuts extending between said key-hole slots and the slots in the stove-pipe section and a spacer thereon between said ring and stove-pipe section.
7. In a device of the character described, a ring-shaped member, a cooperable stove-pipe section and means for pivotally associating said section of stove-pipe within said ring and which is of smaller diameter than said ring so that said stove-pipe section may be received thereby at various angles to the horizontal, said ring-shaped member being provided with diametrically opposite slots, over which slots shields are disposed, and said means extending radially through said slots and the generally concentrically disposed stove-pipe.
8. In a device of the character described, a ring-shaped member, a cooperable stove-pipe section and means for pivotally associating said section of stove-pipe within said ring and which is of smaller diameter than said ring so that said stove-pipe may be received thereby at various angles to the horizontal, said ring-shaped member being provided with diametrically opposite slots, over which slots shields are disposed, and said means extending radially through said slots and the generally concentrically disposed stove-pipe which is also provided with slots with which said means is cooperable.
9. In a device of the character described, a slotted ring-shaped member, and means for pivotally associating a cooperable section of stove-pipe within said ring and of smaller diameter than said ring so that said stove-pipe section may be receivable thereby at various angles to the horizontal, said means including bolts with non-round shanks cooperable with the slotted ring-shaped member and spacer members thereon.
10. In a device of the character described, a slotted ring-shaped member, and means for pivotally associating a cooperable section of stove-pipe within said ring and of smaller diameter than said ring so that said stove-pipe section may be received thereby at various angles to the horizontal, said means including bolts with non-round shanks cooperable with the slotted ring-shaped member and spacer members thereon, said bolts being

threaded only on the corners of the shank thereof.

11. An article of manufacture comprising a ring-shaped member, having diametrically opposite slots, box-like shields on the outer surface of said ring-shaped member and overlying said slots, bolt members extending radially inwardly through said slots and positioning and securing instrumentalities on said bolts for an associative cooperating member.

12. An article of manufacture comprising a ring-shaped member, having diametrically opposite slots, box-like shields on the outer surface of said ring-shaped member and overlying said slots, bolt members extending radially inwardly through said slots and positioning and securing instrumentalities on said bolts for an associative cooperating member, said instrumentalities including spacing elements and nut and washer assemblies.

13. An adjustable flue connection comprising a ring adapted to be embedded in the brickwork of a chimney flush with the room-side of said chimney, having diametrically opposite slots therein, means for preventing movement of said ring and for protecting said slots, a stove-pipe section having di-

ametrically opposite slots, and means for maintaining said stove-pipe section in desired relation to said ring, said means comprising bolts extending through the slots in said ring and through the slots in the stove-pipe section and a spacer thereon between said ring and stove-pipe section, there being a suitable nut on the inner end of each such bolt.

14. An adjustable flue connection comprising a ring adapted to be embedded in the brickwork of a chimney flush with the room-side of said chimney, having diametrically opposite slots therein, means for preventing movement of said ring and for protecting said slots, a stove-pipe section having diametrically opposite slots, and means for maintaining said stove-pipe section in desired relation to said ring, said means comprising bolts extending through the slots in said ring and through the slots in the stove-pipe section and a spacer thereon between said ring and stove-pipe section, said stove-pipe section being receivable in different diameters and said spacer being correspondingly different in length, and nuts on the inner ends of said bolts.
